CLAIM

The ornamental design for a body of display cabinet as shown and described.

DESCRIPTION

1. Body of display cabinet
1.1 : Right perspective view
1.2 : Left perspective view
1.3 : Front
1.4 : Back
1.5 : Left
1.6 : Top
1.7 : Top perspective view
1.8 : Partial enlarged view of the area 1.8 shown in 1.1
1.9 : Cross-sectional view taken along line A-A in 1.3
1.10 : Partial enlarged view of the area 1.10 shown in 1.7
The broken lines depict portions of the body of display cabinet that form no part of the claimed design; reproduction 1.1 is a right perspective view of the body of display cabinet; reproduction 1.2 is a left perspective view thereof; reproduction 1.3 is a front view thereof; reproduction 1.4 is a back view thereof; reproduction 1.5 is a left view where the right view is a mirror image; reproduction 1.6 is a top view where the bottom view is a mirror image; reproduction 1.7 is a top perspective view thereof; reproduction 1.8 is a partial enlarged view of the area 1.8 as identified in reproduction 1.1; reproduction 1.9 is a cross-sectional view taken along line A-A in reproduction 1.3; reproduction 1.10 is a partial enlarged view of the area 1.10 as identified in reproduction 1.1.

(Continued)

1.7; this design is for a body of display cabinet that can display products such as bags; this design has two vents at the bottom.
